UNITED STATES PATENT OFFICE

HANS BÉCHÉ, OF HUCKESWAGEN, GERMANY

DROP HAMMER

Application filed November 10, 1926, Serial No. 147,431, and in Germany November 14, 1925.

My invention relates to improvements in drop hammers, and more particularly in drop hammers in which the ram is operated by a piston reciprocating within a cylinder having a supply of steam or compressed air. In drop hammers of this type such as are now in use the ram is connected with the piston rod by means of a rope, or it is directly connected therewith. As is known to those skilled in the art both constructions are objectionable. Even if ropes are properly treated by skilled labourers they are subject to rapid wear, and if the hammer is operated by unskilled labourers the ropes are frequently broken. In constructions in which the ram is directly connected to the piston rod the said piston rod is frequently broken even if liquid brakes are interposed between the rod and the ram. Further, the construction is comparatively high, so that in most cases the height to which the ram can be lifted is limited. The object of the improvements is to provide a drop hammer in which the aforesaid objections are obviated. With this object in view my invention consists in providing a hammer in which the ram is loosely engaged by the piston rod, and in which the guide way for the ram is extended upwardly so far that the ram is thrown upwardly by the impact imparted thereto by the piston beyond the end of the working stroke of the piston. Therefore the height of the hammer is comparatively small, and only the guide ways of the ram are comparatively high. Thus I am enabled to provide a hammer in which the ram can be thrown to a considerable height even in low work shops. Thus the hammer can be provided in work shops which by reason of their small height did not allow the mounting of the hammer.

For the purpose of explaining the invention an example embodying the same has been shown in the accompanying drawing, in which the same letters of reference have been used in all the views to indicate corresponding parts. In said drawing,

Fig. 1, is an elevation of the hammer partly in section, and

Fig. 2, is an elevation looking from the right in Fig. 1.

In the example shown in the figures my improved hammer consists of an anvil *a* having guide rods *f* secured thereto, and a ram *g* guided on the said rods. At opposite sides of the anvil vertical cylinders *b* are mounted in which pistons *o* have reciprocating movement, the rods *n* of which are formed with heads *d*, *e* loosely engaging the ram *g*. To the bottom ends of the cylinders a suitable driving fluid such as steam or compressed air is admitted through a flexible tube *h*, the supply of the pressure fluid being controlled by an intake valve *i* and a discharge valve *k* the bodies of which are controlled in a suitable way by a lever *m*. As shown in the figures the cylinders *b* are disposed in vertical holes made in the anvil, and the controlling valves *i* and *k* are located at the side of the anvil and independently thereof. But I wish it to be understood that I do not limit myself to these features, and that in some cases the cylinders *b* are separate from the anvil, and in other cases the valves are mounted on the anvil.

When opening the intake valve *i* the pistons *o* and piston rods *n* are thrown upwardly, and the ram *g* is lifted by the heads *d*, *e* of the piston rods. After closing the intake valve the ram is thrown upwardly beyond the end stroke of the pistons *o*, whereupon it freely falls downwardly, the piston rods *d*, *e* having been in the meantime returned into their initial positions. The heads *d* and *e* thus constitute means abutting the ram *g* to actuate the ram by giving an impulse thereto. In some cases I provide elastic means such as an air buffer at the top end of the guide ways *f* by means of which injury to the top end of the buffer is prevented and a part of the power of the upwardly moving ram is stored and imparted to the ram at the beginning of the downward stroke. In the figures an air buffer consisting of a cylinder *p* and a plunger *q* is provided at the top end of the guide rods *f*. The pistons *o* are elastically arrested at the ends of their strokes by elastic fluid being confined within the cylinders at the upper and lower ends thereof. As appears

from Fig. 1 the outlet ports *r* are located a suitable distance away from the upper head of the cylinder, and in a similar way the intake and outlet passage *s* for the pressure fluid is located a suitable distance above the bottom end of the cylinder.

The height to which the ram is thrown upwardly is controlled by interrupting the supply of the pressure fluid at a suitable point of the upward stroke of the piston.

The pistons *d* and *e* are provided with dash pots *d'* *e'*, respectively, on top of the base *a*, and the rods of these pistons pass through the bottoms of the dash pots into the cylinders *b*. These dash pots cushion the downward movement of the pistons *o* when the ram *g* is dropped.

While in describing the invention reference has been made to a particular example embodying the same I wish it to be understood that my invention is not limited to the construction shown in the drawing, and that various changes may be made in the general arrangement of the apparatus and the construction of its parts without departing from the invention.

I claim:

1. A power hammer, comprising an anvil formed at its sides with vertical cylindrical holes, a ram, pistons mounted in said holes for reciprocating therein and loosely engaging said ram, means to supply a pressure fluid to said holes below said pistons, and guiding means for said ram.

2. A power hammer, comprising an anvil, a ram, vertical cylinders in said anvil at the sides thereof, pistons reciprocating in said cylinders and loosely engaging said ram, valve mechanism controlling the supply of pressure fluid to said cylinders and having a flexible connection with said cylinders, and guiding means for said ram.

3. A power hammer comprising a base, an anvil thereon, a ram, a guide structure wherein the ram is guided for vertical reciprocation, said structure extending upward from the base and the height of said structure being limited substantially to that required for ram-travel, a cylinder associated with the base, a piston therein, and a piston rod having free contact with an underpart of the ram for driving the latter upward, the piston and rod being free to return to lower position while the ram is in elevated position in the guide structure.

4. A power hammer comprising a base, an anvil thereon, a ram, a guide structure wherein the ram is guided for vertical reciprocation, said structure extending upward from the base and the height of said structure being limited substantially to that required for ram-travel, a cylinder associated with the base, a piston therein, and a piston rod having free contact with an underpart of the ram for driving the latter upward, the

cylinder and piston rod being dimensioned to propel the ram positively only part-way upward in the guide structure, and means for controllably supplying propulsive fluid to the cylinder to propel the piston rod and ram rapidly and positively upward to the end of the piston-stroke, whereafter the ram travels farther upward by momentum.

5. A power hammer comprising a base, an anvil thereon, a ram, a guide structure wherein the ram is guided for vertical reciprocation, said structure extending upward from the base and the height of said structure being limited substantially to that required for ram-travel, a cylinder associated with the base, a piston therein, and a piston rod having free contact with an underpart of the ram for driving the latter upward, the piston and rod being free to return to lower position while the ram is in elevated position in the guide structure, the cylinder having a discharge port positioned to provide a cushioning-pocket in the cylinder to check the piston near the upper end of its stroke.

6. A power hammer comprising a base, an anvil thereon, a ram, a guide structure wherein the ram is guided for vertical reciprocation, said structure extending upward from the base and the height of said structure being limited substantially to that required for ram-travel, a cylinder associated with the base, a piston therein, and a piston rod having free contact with an underpart of the ram for driving the latter upward, the piston and rod being free to return to lower position while the ram is in elevated position in the guide structure, the piston rod having near its upper end a dash-piston, and an upwardly-open dash-cylinder about the rod at the upper end of the main cylinder, the dash-piston cooperating with the dash-cylinder to check the piston rod and main piston near the end of their return stroke.

7. A power hammer comprising a base, an anvil thereon, a ram, a guide structure wherein the ram is guided for vertical reciprocation, said structure extending upward from the base and the height of said structure being limited substantially to that required for ram-travel, a cylinder associated with the base, a piston therein, and a piston rod having free contact with an underpart of the ram for driving the latter upward, the cylinder and piston rod being dimensioned to propel the ram positively only part-way upward in the guide structure, and means for controllably supplying propulsive fluid to the cylinder to propel the piston rod and ram rapidly and positively upward to the end of the piston-stroke, whereafter the ram travels farther upward by momentum, and a yielding buffer at the upper end of the guide structure to check the ram at the upper end of its maximum stroke.

8. A power hammer comprising an anvil.

a ram, guides extending upwardly a considerable distance above the anvil and in which the ram is mounted for reciprocation, the height of said guides being limited substantially to that required for ram-travel, and actuating means abutting the ram and adapted to drive the same upwardly from the anvil, said actuating means being disconnected from the ram and having a maximum stroke less than the extent of said guides whereby the ram will be driven the full length of the stroke and said actuating means and so as to travel well beyond the maximum stroke thereof and until its upward momentum is expended.

9. A power hammer comprising an anvil, a ram, guides extending upwardly a considerable distance above the anvil and in which the ram is mounted for reciprocation, the height of said guides being limited substantially to that required for ram-travel, actuating means abutting the ram and adapted to drive the same upwardly from the anvil, said actuating means being disconnected from the ram and having a maximum stroke less than the extent of said guides whereby the ram will be driven the full length of the stroke of said actuating means and so as to travel well beyond the maximum stroke thereof and until its upward momentum is expended, said actuating means being free to return to its initial position while the ram is in elevated position in the guides.

10. A power hammer comprising an anvil, a ram, guides extending upwardly a considerable distance above the anvil and in which the ram is mounted for reciprocation, the height of said guides being limited substantially to that required for ram-travel, cylinders having pistons loosely engaging the underside of the ram and adapted, when actuated, to drive the ram upwardly from the anvil, said pistons having a maximum stroke less than the extent of said guides whereby the ram will be driven well beyond the maximum stroke of the pistons and until its upward momentum is expended.

11. A power hammer comprising an anvil, a ram, guides extending upwardly a considerable distance above the anvil and in which the ram is mounted for reciprocation, the height of said guides being limited substantially to that required for ram-travel, cylinders having pistons loosely engaging the underside of the ram and adapted, when actuated, to drive the ram upwardly from the anvil, said pistons having a maximum stroke less than the extent of said guides whereby the ram will be driven well beyond the maximum stroke of the pistons, and a buffer arranged on said guides to receive the impact of said ram.

In testimony whereof I hereunto affix my signature.

HANS BÉCHÉ.
